BASE FOR FIREPLACES, STOVES, BARBECUE GRILLES AND THE LIKE

Robert D. Thulman, 10002 Frederick Ave.,
Kensington, Md.

Filed July 12, 1965, Ser. No. 86,113

Term of patent 3½ years

(Cl. D81—7)

FIG. 1 is a perspective view of the base, with a device supported thereby indicated in broken lines for illustrative purposes only.

FIG. 2 is an elevation view of the base taken from the side as viewed in FIG. 1.

FIG. 3 is an elevation view of the base taken at right angles to FIG. 2.

I claim:

The ornamental design for a base for fireplaces, stoves, barbecue grilles and the like, as shown and described.
